PROCESS FOR THE ALKYLATION OF ISOPARAFFINS

Filed Jan. 30, 1939

UNITED STATES PATENT OFFICE

2,286,504

PROCESS FOR THE ALKYLATION OF
ISOPARAFFINS

Farrand D. Parker, Los Angeles, Calif., assignor
to Union Oil Company of California, Los Angeles, Calif., a corporation of California

Application January 30, 1939, Serial No. 253,502

6 Claims. (Cl. 196—10)

This invention relates to the treatment of hydrocarbon oils, and refers more particularly to the production of valuable gasolines by synthetically reacting the lighter and less valuable portions of crude petroleum products and similar hydrocarbon mixtures. In a more specific sense, the invention has reference to a process which may be employed to supplement known crude oil treating processes to increase the obtainable yield of high anti-knock fractions suitable for use as fuel in internal combustion engines, or as constituents thereof.

The comparatively recent adoption of high compression ratios in automobile and aviation engines to increase their thermodynamic efficiency placed a demand on the petroleum refining and similar industries to furnish hydrocarbon motor fuels of high anti-knock or slow burning characteristics. As a partial attempt to satisfy this requirement the petroleum industry has resorted to the use of cracking operations in which the relatively higher boiling hydrocarbon fractions are subjected to elevated temperatures and frequently super-atmospheric pressures to cause the decomposition of these hydrocarbons and to produce fractions within the motor fuel boiling range.

However, these cracking operations are not entirely satisfactory both from the standpoint of yields and the quality of the produced motor fuels. Thus, among other objections, the motor fuels derived from such cracking of petroleum oils or their fractions do not possess the desired high anti-knock characteristics. Nor are these fuels sufficiently susceptible to the action of substances of the type of tetraethyl lead. In other words, such lead compounds, when added in quantities within the permissible range, are incapable of raising sufficiently the knock-rating characteristics of the motor fuel fraction thus treated. Furthermore, all cracking processes produce more or less appreciable quantities of normally gaseous hydrocarbons of varying compositions which, if not utilized, represent wasted natural resources. These normally gaseous fractions, resulting as a by-product from the cracking of petroleum oils, contain considerable proportions of olefins, particularly of the type of propylene and butylenes. In connection with the operations of most modern petroleum refineries, there are several sources of such olefin-containing normally gaseous fractions. One of these is the gaseous fraction produced as the result of releasing the pressure on the petroleum oils which are being subjected to a cracking treatment. Although relatively large percentages of methane are usually present in this

fraction, it also contains other petroleum hydrocarbons, including appreciable quantities of olefins ranging from ethylene into the normally liquid olefinic hydrocarbons which have been carried out of the cracking zone by the released gases. Generally, in modern refinery operations, these hydrocarbon fractions are subjected to a treatment with an absorbing medium to recover most if not all of the entrained normally liquid hydrocarbons. The remaining gaseous fraction contains varying proportions of olefins of the type of propylene and butylenes, as well as some saturated hydrocarbons such as methane, ethane, propane and butanes. Another source of the refinery gases is the overhead or reflux fraction obtained from the stabilization of pressure distillate resulting from cracking petroleum oils under pressure. These fractions generally predominate in olefines of the type of propylene and butylenes, usually containing only very small percentages of methane. Obviously, the composition of the different gases will vary considerably depending on the stock subjected to cracking, as well as on the specific cracking and recovery processes employed.

Recently, it has been proposed to produce synthetic motor fuel fractions by contacting isoparaffinic or aromatic hydrocarbons with olefins in the presence of a suitable catalyst adapted to produce a chemical combining of these hydrocarbons. The resulting product may be termed a "product of alkylation," and may be generally described as consisting of saturated or cyclic hydrocarbon molecules with hydrocarbon chains or branches attached thereto. The above nomenclature was employed to distinguish this branched chain molecule from a polymer which is a product resulting from the interaction of two or more olefinic molecules to produce an unsaturated hydrocarbon molecule having a correspondingly higher molecular weight. As an example of an alkylation reaction and of the resulting product, reference may be made to the chemical combining of propylene or butylene with isobutane to produce seven or eight carbon atom branched chain saturated molecules, respectively.

It has been recently discovered that optimum operating conditions for the alkylation reaction depend on the particular isoparaffins and olefins employed. Thus, whereas a given temperature and pressure may be highly suitable for the production or formation of products of alkylation by the interaction of isobutane with butylenes in the presence of strong sulfuric acid, the same operating conditions when applied to the catalytic

treatment of isopentane with butylene or propylene may cause the production of excessive quantities of polymers. For this reason it has been generally considered advisable to produce relatively narrow cuts or fractions predominating in a given isoparaffin, and to catalytically alkylate these individual isoparaffinic fractions with the olefins to produce optimum yields of products of alkylation. Furthermore, since normal paraffins do not react with olefins unless subjected to decomposing temperatures and pressures, it is advisable to fractionate the paraffinic hydrocarbons so as to isolate the particular isoparaffin even from its corresponding normal paraffinic hydrocarbon before the isoparaffinic hydrocarbon fraction is employed in the alkylation reaction. Obviously such procedure necessitates the use of special equipment for the narrow fractionation of the saturated hydrocarbons, thus greatly increasing the initial and operating costs of an alkylation plant.

As previously stated, products of alkylation are formed by the catalytic interaction of isoparaffins and olefins. Generally, this alkylation is conducted in a liquid phase, the liquefied isoparaffins such as isobutane or isopentane being first intimately commingled with the liquefied olefin-containing fraction before the mixture is brought into contact with the alkylating catalyst such as sulfuric acid, a mixture of sulfuric and phosphoric acids or a metal halide catalyst such as aluminum chloride. Since the olefins are relatively highly reactive and tend to form polymers in preference to their alkylation of the isoparaffins, it is desirable, if not essential, to maintain an excess of the isoparaffinic hydrocarbon fraction, or of the products of alkylation. Although the isoparaffinic hydrocarbon employed for the production of high anti-knock motor fuels may be obtained from other sources, these isoparaffins, and particularly isobutane, isopentane and isohexane, are mainly derived from the stabilization of gasolines extracted from natural gases. Thus, although the fractions employed as reflux for such natural gasoline stabilization are in a liquefied state and predominate in propane, these fractions may in turn be fractionated to produce an isobutane predominating cut. A comparable material may be produced as a side-cut during stabilization of the natural gasoline. The isopentane and isohexane fractions may be recovered from the fractionation of stabilized natural gasoline. On the other hand, the olefinic fractions obtained as a by-product from cracking operations are often in a gaseous state so that if the alkylation reaction is to be realized in a liquid state, these olefin-containing gases must be liquefied, thus further adding to the cost of the operations.

It is, therefore, the main object of the present invention to avoid the above difficulties and to provide a novel process for obtaining increased yields of high anti-knock motor fuel fractions by means of new and novel cooperation of certain steps to be described more fully hereinbelow. A further object of the present invention is to obtain a motor fuel fraction having a high anti-knock value and substantially free from products of polymerization by processing a mixture of normally gaseous olefin-containing hydrocarbons derived from petroleum oil conversion or cracking processes, and liquefied saturated normally gaseous hydrocarbons containing isoparaffinic fractions without the necessity of providing special or separate equipment for the narrow fractionation

of the isoparaffin-containing or isoparaffinic hydrocarbon fractions.

A further object of the invention is to provide an alkylation process for the production of high anti-knock motor fuel fractions in which process the separate fractionation of the isoparaffinic hydrocarbon is eliminated.

10 A still further object of the present invention is to conduct the alkylation of isoparaffinic hydrocarbons, and preferably the isobutane, isopentane and/or isohexane fractions with normally gaseous olefins and olefin-containing gases, in a liquid state and in the presence of a catalyst of the type described above, without the necessity 15 of providing means for the expensive compression and liquefaction of the olefin-containing fractions.

20 Another object of the invention is to produce branched chain saturated hydrocarbons boiling within the gasoline range, having high anti-detonating characteristics and substantially free from unsaturated hydrocarbons within the gasoline range, this process being economical and adapted to utilize a fluctuating supply of gaseous hydrocarbons of various compositions.

25 It has now been discovered that some of the above and other objects may be attained by contacting the gaseous olefin-containing fractions with a liquid medium adapted to absorb the olefinic constituents from the gaseous fractions, and by contacting this liquid medium, and the olefins thus liquefied, with the liquid isoparaffinic hydrocarbons, at optimum temperatures and in the presence of an alkylating catalyst, such as strong 30 sulfuric acid. The resulting product of alkylation, or some portion or fraction thereof may be used as the absorbing medium. By such operation, the liquid product of alkylation is thus employed both for the purpose of absorbing (and thus liquefying) the olefins, and to dilute, and thus lower the concentration of olefins in the reaction zone, thereby promoting the alkylation of the introduced isoparaffins, with the concurrent 35 inhibition of polymer formation.

40 It has also been discovered that a considerable saving in initial and operating expenses may be realized by eliminating any special fractionating structures for the recovery of the substantially pure isoparaffinic fraction, such as isobutane, isopentane or isohexane, from the hydrocarbons containing the same, and by fractionally treating these isoparaffin-containing hydrocarbons together with the crude products of alkylation recovered from the catalytic treatment of isoparaffins with olefins. It is to be noted that the crude liquid fraction produced as a result of the interaction of an isoparaffinic fraction (such as a hydrocarbon fraction predominating in isobutane) with an olefin-containing hydrocarbon fraction, comprises a heterogeneous liquid mixture which contains true products of alkylation, relatively large percentages of the isoparaffinic hydrocarbon being alkylated, and relatively smaller quantities of other gaseous hydrocarbons which have been dissolved in the liquid product. Furthermore, even the true products of alkylation themselves comprise a mixture of hydrocarbons having different boiling points resulting from the chemical combining of the isoparaffins with the different olefins entering the reaction zone. In view of this heterogeneous character of the crude product, the separation and recovery of the desired hydrocarbon fraction boiling within the gasoline range, necessitates a fractionation of the crude reaction product. According to 45

the present invention, this same fractionation is utilized for the treatment of the isoparaffin-containing hydrocarbon fraction to recover therefrom the specific isoparaffin, such as isobutane, in a substantially pure state, this isoparaffinic fraction being recovered as a liquid and utilized as the feed or starting material for the formation of additional quantities of products of alkylation.

The invention further includes processes in which the above outlined steps are employed in combination with other steps such as: the recycling of a portion of the crude products of alkylation to maintain suitable ratios of products of alkylation, isoparaffins and olefins in the reaction zone; recycling of the acid and/or hydrocarbon acid mixture or emulsion to alkylate new quantities of isoparaffins and olefins; dehydration of the hydrocarbons prior to their introduction into the reaction zone and into contact with the catalyst such as strong sulfuric acid; and the desulfurization of the olefinic hydrocarbons. The invention further includes an alkylation process of the class described in which a portion of the products of alkylation, and particularly the heavy fraction boiling above the gasoline boiling range, may be efficiently employed as the medium for the heating of the various fractionating towers, thus furnishing the heat necessary for the fractionation of the crude alkylation reaction product and of the isoparaffin-containing hydrocarbons.

The invention will be further understood from the following description of an embodiment of the invention, this description being made with reference to the accompanying drawing which forms a part of the specification and which represents a diagrammatic elevational view of an apparatus suitable for carrying out the present process.

Referring to the drawing, the olefin-containing normally gaseous hydrocarbon fraction is charged into the system through conduit 10. Since in the present process the alkylation reaction described more fully hereinbelow is conducted in a liquid phase, the olefinic fraction introduced through line 10 may be a portion of the condensed reflux fraction obtained during the stabilization of pressure distillate resulting from petroleum cracking operations. In the alternative, the overhead gaseous fraction derived during such stabilization of cracked pressure distillate may also be used as the charging stock. Obviously, such gaseous fractions should be preliminarily condensed by any suitable and known methods and means. Both the overhead gaseous fraction and the reflux portion thereof contain relatively large quantities of olefins, the propylene-butylene content of such fractions usually exceeding 20%, and in most cases being above 30% or even 35%.

The so-called "lean gases" resulting from the ordinary absorption treatment of gaseous fractions produced during the release of pressure on the cracked petroleum product, are also a suitable source for the obtaining of olefins which may be employed in the alkylation process. This gaseous fraction, although containing relatively large quantities of methane and ethane, also contains appreciable proportions of olefins of the type of propylene and butylenes which are suitable for use in the process to be described. Thus, these lean gases contain as much as 10 to 15% of propylene and butylenes. These lean gases may be introduced into the system through line 12,

wherein they are first cooled as by passage through a chiller 13. This chiller may be eliminated if the gases are available at a suitably low temperature. In order to obtain a liquid olefin-containing fraction, as well as for the purpose of selective extraction of the desirable olefins, these cooled lean gases are then passed into an absorber 14 in which they are brought into contact with a fraction of the products of alkylation. As will be described more fully hereinbelow, the lean oil used in the present process as the absorbing medium in absorber 14 is the heaviest fraction resulting from the fractionation of the products of alkylation. It is to be understood, however, that other fractions of the products of alkylation, as well as other absorbing media, may be used to extract the desired olefins from the lean gases.

The lean oil to be used in the above described absorption is first cooled in a heat exchanger 16 and is then continuously fed through line 17 into absorber 14. The rich oil thus formed (comprising the products of alkylation and the olefin-containing gases absorbed thereby) is withdrawn through line 18, and, after further cooling in heat exchanger 19, is conveyed through line 20 and into line 10 to be commingled with the first mentioned liquefied olefin-containing gaseous fraction. The gases which are not absorbed by the lean oil are removed from the system through line 22 leading from the upper part of absorber 14.

The liquid fraction thus entering the system through line 10 is first subjected to a desulfurization operation for the removal of the hydrogen sulfide usually present in the olefin-containing normally gaseous hydrocarbons. Although the hydrogen sulfide content of such hydrocarbons is relatively small, being in the neighborhood of 0.25%, it has been found that the removal of this sulfide is beneficial and results in better yields of products of alkylation, as well as in greater economy. To effect the removal of the hydrogen sulfide the olefin-containing liquid fraction is conveyed into a vessel 25 wherein it is brought into contact with an aqueous solution of an alkaline compound having an affinity for hydrogen sulfide. As an example, vessel 25 may be filled with an aqueous solution of sodium carbonate. The desulfurized hydrocarbons then leave the vessel 25 through line 26, while the sodium carbonate solution containing the absorbed sulfur compound is withdrawn through line 27 and conveyed into the top of a regenerating vessel 28 in which the foul sodium carbonate is brought in contact with an upward draft of air introduced through line 31. The rejuvenated sodium carbonate solution is then withdrawn from the bottom of tank 28 and is returned through line 29, either continuously or intermittently, back into vessel 25 for further desulfurization of the olefin-containing hydrocarbon fractions. The air containing the hydrogen sulfide is withdrawn from the upper part of the regenerating tank 28 through pipe or vent 30.

As previously discovered, the alkylation of isoparaffins of the type of isobutane, isopentane and isohexane is best realized in the presence of a relatively strong sulfuric acid, for example, sulfuric acid having approximately a 98% H_2SO_4 content. Since any water present will naturally dilute the sulfuric acid catalyst, it is desirable to dehydrate the hydrocarbons prior to their contact with such strong sulfuric acid catalyst. Therefore, for the purpose of removing any water

which may be present in the olefin-containing liquid hydrocarbon fraction, the desulfurized fraction leaving vessel 25 through line 26 is conveyed through a drier 34 which may contain any known drying material such as sodium sulfate. Although only one such drying tank is shown in the drawing, it is obvious that a plurality of such tanks may be placed parallel so that any one of the tanks may be isolated for the purpose of regenerating the sodium sulfate or for the purpose of recharging the drier with fresh dessicant, without the necessity of completely stopping the operations of the whole system.

The desulfurized and dried hydrocarbon fraction containing the normally gaseous olefins now in solution, is then conveyed through line 35 into line 36 wherein it is commingled with the crude products of alkylation coming from line 38, and with the liquefied isoparaffins, such as isobutane, continuously fed through line 39. The isoparaffin-olefin mixture then passes through line 40 and is then contacted with fresh catalyst introduced through line 41 and with used catalyst coming through line 42. For the purpose of intimate commingling, the mixture then passes through a mixer or agitator 44, after which the mixture is cooled in chiller 45 to remove the exothermic heat of reaction.

In order to prevent the polymerization of the olefins, while promoting the alkylation reaction between the isoparaffins and the olefins, it is desirable, if not essential, to maintain an excess of the isoparaffins and of the crude products of alkylation. Obviously, the presence of excess isoparaffins (such as isobutane) in the hydrocarbon mixture passing through mixer 44 results in the presence of unreacted isoparaffins in the stream being conveyed therefrom through line 46. After passage through cooler 45, this hydrocarbon stream (while in a state of emulsification or commingled with the sulfuric acid or other catalyst) is divided into two portions. One of these is conveyed through lines 48 and 38 for purposes of recycling while the other is conveyed through line 49 into settler 50. The sulfuric acid settles to the bottom of this settler 50 and is withdrawn through line 52. As stated, this acid may be recycled by conveying it through line 42 which leads this acid catalyst to line 40 wherein it is continuously commingled with fresh quantities of hydrocarbons to be alkylated. The acid when incapable or uneconomical for alkylation of further quantities of isoparaffins and olefins, may be withdrawn through line 53, while, as stated, fresh acid or the like may be introduced into the system through line 41.

The supernatant layer, comprising the products of reaction and the excess isoparaffins, is withdrawn from the top of settler 50 through line 55 and is neutralized for the purpose of removing any traces of acid which may find their way into the hydrocarbon phase recovered from the settler 50. For this purpose the stream passing through line 55 is commingled with a neutralizing agent, such as sodium hydroxide, coming from line 56. The mixture is then thoroughly commingled in mixer or agitator 57, and is then passed through line 58 into another settler 59. Here, the sodium hydroxide deposits itself to the bottom and may be withdrawn from the bottom through line 60. This neutralizing agent may then be recycled through lines 62 and 56 for the washing of further quantities of the hydrocarbons being conveyed

through line 55. Obviously, when necessary the neutralized alkali may be withdrawn from the system through line 63, while fresh alkali may be introduced into the system through the same or another pipe.

The neutralized hydrocarbon mixture, comprising products of reaction and unreacted isoparaffins, is continuously withdrawn as the supernatant layer, from settler 59, and is conveyed through line 66 to a fractionating system to be described more fully hereinbelow.

In view of the fact that the alkylation reaction is realized at atmospheric and even sub-atmospheric temperatures as low as 10°-15° F., this low temperature may be utilized to precool both the isoparaffins and the olefins which are being conveyed continuously to the alkylation portion of the system. For this purpose, the cold products of alkylation passing through line 66 are first conveyed through heat exchanger 68 in which they are brought into indirect contact with the isoparaffinic fraction (such as isobutane) passing through line 94 to dehydrating tank 37 from which the liquefied cold isoparaffins are then conveyed to the alkylating zone described above.

After passing through heat exchanger 68, the slightly warmed hydrocarbon mixture is then conveyed through line 69 to a surge tank 70, from which the mixture is conveyed through line 71, heat exchanger 19, line 72, and heat exchanger 16. In the first of these heat exchangers, the hydrocarbon mixture precools the olefin-containing absorbing medium passing through lines 18 and 20, while in heat exchanger 16, the products of reaction are heated by the lean absorbing medium fed into absorber 14 through line 17.

The mixture of preheated reaction products leaving preheater or heat exchanger 16 is conveyed through line 74 into the first of a series of fractionating columns. However, prior to such introduction into the fractionating system, the crude products of alkylation are first commingled with an isoparaffin-containing fraction introduced into the system through line 75. As previously stated, this isoparaffin-containing fraction may be a hydrocarbon mixture containing both normal and isomeric paraffins (such as normal butane, isobutane, etc.), this hydrocarbon mixture being derived either as a side-cut or fraction, or as a reflux fraction in the stabilization of natural or straight run gasolines.

The fractionation of the isoparaffin-containing hydrocarbons and of the products resulting from the alkylation reaction is realized according to the present invention in a plurality of fractionating columns. As shown in the drawing, the mixture passing through line 74 first enters fractionator 77 which is maintained at optimum temperatures and pressures to cause the vaporization of the lightest hydrocarbons of the type of methane, ethane, and propane. The heating of fractionator 77, as well as of the succeeding fractionator, is realized by method and means to be described more fully hereinbelow. The hydrocarbon vapors in fractionator 77 are withdrawn therefrom through line 78. A portion of this overhead fraction is cooled at 79 and the condensate thus formed is returned as reflux through line 80 back into the upper portion of fractionator 77. The remaining portion of the gaseous overhead fraction may be withdrawn from the system through line 82, while any non-condensed gases from cooler 79 may be with-

drawn through line 83. The hydrocarbons remaining in the liquid state in fractionator 77 are withdrawn from the bottom thereof through line 85 and are conveyed therethrough to the second fractionator 86. A portion of the bottom fraction thus withdrawn through line 85 is by-passed through 87 and is conveyed through a heater or reboiler 88 and then returned through line 89 back into fractionator 77 to provide the above described heat necessary for the vaporization of the propane or the lighter gaseous hydrocarbons. The heat for the reboiler 88, as stated above, is provided from a source described hereinbelow. The hydrocarbons stripped of the lightest fractions and introduced into fractionator 86 are again fractionated in this tower so as to cause the vaporization and withdrawal, as an overhead fraction, the hydrocarbons predominating in or substantially consisting of isobutane. For this purpose fractionator 86 is maintained at a desired or optimum temperature or pressure. The overhead fraction formed is withdrawn from the top of this fractionator through line 91, condensed in cooler 92, and a portion returned through line 93 back into fractionator 86, this liquefied hydrocarbon fraction acting as a refluxing medium. The remaining isobutane fraction condensed at 92 is conveyed through line 94 for use as the isoparaffinic hydrocarbon fraction to be alkylated. For this purpose, this isobutane fraction is first partially precooled by passing it through the heat exchanger 68 and through tank or drier 37 in which the hydrocarbon fraction is dehydrated as by means of sodium sulfate or a similar desiccating medium. The dried isobutane, as described above, thus passes through line 39 to lines 36 and 40 wherein it is commingled with crude products of alkylation, olefins and the acid catalyst.

The hydrocarbon mixture remaining as a liquid in fractionator 86 is withdrawn from the bottom thereof through line 97 and is conveyed to the last fractionator 98. As in the case of the first fractionator 77, a portion of the bottom fraction withdrawn by 97 from fractionator 86 is by-passed through line 99 and is conveyed through heater 100 and back into the fractionator through line 101. Instead of by-passing only a portion of the bottom fractions withdrawn from fractionators 77 and 86 through lines 87 and 99 respectively, it is also possible to convey the whole bottom fractions through their respective reboilers or heaters 88 and 100. In such a case the vaporized portions therefrom in these reboilers may be returned through lines 89 and 101 to their respective fractionators for the purpose of providing the necessary heat for fractionation therein. Unvaporized hydrocarbon fractions may then be withdrawn from the reboilers and conveyed to the succeeding fractionating columns.

The normal butane fraction vaporized in fractionator 86 is withdrawn as a side-cut from this fractionator through line 102 provided with a valve 103. This normal butane cut, if desired, may be condensed and withdrawn from the system to be used for various purposes such as stabilization of pressure distillate or natural gasoline, or it may be subjected to isomerization to form additional quantities of isobutane, thus increasing the potential yield of products of alkylation. The liquid hydrocarbon fraction introduced through line 97 into the last fractionator 98 predominates in products of alkylation. However, in view of the relatively wide boiling range of

these products of alkylation, the hydrocarbons in fractionator 98 may be subjected to a fractionation so as to obtain three cuts. By maintaining fractionator 98 at optimum temperatures and pressures an overhead fraction is produced, which may comprise a hydrocarbon fraction suitable as a fuel for aviation engines. Thus by suitable operation of the fractionator 98 it is possible to obtain an overhead fraction having an end point of about 325° F. which is the end boiling point of aviation gasoline. This overhead fraction is removed from the top of fractionator 98 through line 105 and is condensed in cooler 106. A portion of liquefied gasoline fractions is returned through line 107 back into the fractionator and is used therein as a reflux medium, while the remaining aviation gasoline fraction is withdrawn from the system through line 108. The heavier synthetic gasoline fraction is withdrawn as a middle or side-cut through line 109 and may be condensed in 110. This synthetic product of alkylation, although having a higher end point than the overhead fraction withdrawn through line 108, also possesses good anti-knock characteristics and is particularly suitable as a motor fuel for automobiles or as a constituent thereof. The residual fraction remaining unvaporized is withdrawn from the bottom of the fractionator 98 through line 112. A portion of this fraction is by-passed through line 113, precooled in heat exchanger 16 and is used as the absorbing medium in absorber 14. Of the remaining residual fraction withdrawn from fractionator 98, a portion is by-passed through line 114 for use as the heating medium for the fractionating system. For this purpose it is conveyed through said line 114 to a heater 115 wherein it is raised to an optimum or desired temperature. This heated hydrocarbon fraction is then conveyed through line 116 and is employed for heating reboilers 88 and 100 and to provide heat in fractionator 98. For this purpose line 116 communicates with branch lines 118 and 119 leading to reboilers 88 and 100 respectively, the balance of the heated hydrocarbon fraction being conveyed through line 120 into the bottom portion of fractionator 98. After passing through reboilers 98 and 100 the heating medium is returned through lines 122 and 123 respectively back into line 114 leading to heater 115. The net excess heavy products of alkylation withdrawn through line 112 are removed from the system through line 124, provided with a valve 125.

As indicated above, the description of the process is simply illustrative of the invention and is subject to many modifications by those skilled in the art. Thus, although the use of 98% and "strong" sulfuric acid is above indicated it is obvious that the process may be realized while employing other alkylating catalysts. Generally speaking, sulfuric acid of between about 94% and 100% H_2SO_4 content may be employed. Also the catalyst may consist of a mixture of sulfuric and phosphoric acids or may comprise or include chlorosulfonic acid or certain metallic halide complexes such as aluminum chloride or boron trifluoride or catalysts consisting of the above acids in combination with certain metallic salts such as phosphates, sulfates, chlorides, nitrates and acetates of the type of cadmium, zinc, silver, mercury, copper and barium may be used. These salts act as activators to promote the alkylation reaction in preference to the polymerization of the olefins.

Although the process is described in connection with the recycling of a portion of the hydrocarbon acid mixture through lines 38 and 48, it is possible to recycle a portion of the crude products of alkylation from line 55 back into line 38, this hydrocarbon fraction being employed to dilute the olefins and maintain a proper ratio between the products of alkylation, isoparaffins and olefins. Such a procedure would eliminate any extensive contact between the crude products of alkylation and the acid. Furthermore, instead of employing both the olefin-containing fraction derived from the stabilization of pressure distillate and that obtained from the reduction of pressure in the cracking stills, it is possible to use either of these fractions or any other olefin-containing fraction, especially if it is rich in the desirable propylene and butylenes. Furthermore, the absorption of the olefins from the gases entering through 12 may be realized by any other absorbing medium or by a portion of the products of alkylation as formed according to the process of the present invention.

The heating of the reboilers may be realized by employing hydrocarbon fractions other than the heavy reaction products removed from the bottom of fractionator 38. Furthermore, other heating media such as steam may be employed for this purpose. Still further in carrying out the invention the conditions of operation chosen with respect to temperature, proportion of reacting constituents, choices of catalysts, and temperatures and pressures in the fractionating system may be varied within a relatively large range to suit the individual case. Therefore, the above disclosure is merely illustrative and is not to be taken as limiting since many variations may be possible within the scope of the pending claims.

I claim:

1. In a process for the production of branched chain saturated hydrocarbons boiling within the gasoline range wherein isoparaffinic hydrocarbons are reacted with normally gaseous olefinic hydrocarbons in the presence of an alkylating catalyst, the steps of contacting the gaseous olefins with a hydrocarbon liquid absorbing medium prior to contact with said isoparaffin and alkylating catalyst thereby producing a liquid mixture containing the absorbed olefins, commingling said mixture with liquefied isoparaffins to be alkylated and with the alkylating catalyst thereby forming alkylation products comprising said branched chain saturated hydrocarbons and employing said alkylation products as said liquid absorbing medium.

2. In a process for the production of branched chain saturated hydrocarbons boiling within the gasoline range wherein isoparaffinic hydrocarbons are reacted with normally gaseous olefinic hydrocarbons in the presence of an alkylating catalyst, the steps of contacting the gaseous olefins with a hydrocarbon liquid absorbing medium prior to contact with said isoparaffin and alkylating catalyst, thereby producing a liquid mixture containing the absorbed olefins, commingling said mixture with liquefied isoparaffins to be alkylated and the alkylating catalyst, thereby forming reaction products comprising said branched chain saturated hydrocarbons, separating said reaction products into fractions and employing one of said fractions as the said absorbing medium.

3. In a process for the production of branched chain saturated hydrocarbons boiling within the

gasoline range wherein isoparaffinic hydrocarbons are reacted with normally gaseous olefinic hydrocarbons in the presence of an alkylating catalyst, the steps of contacting the gaseous olefins with a hydrocarbon liquid absorbing medium prior to contact with said isoparaffin and alkylating catalyst, thereby producing a liquid mixture containing the absorbed olefins, commingling said mixture with liquefied isoparaffins to be alkylated and the alkylating catalyst, thereby forming reaction products comprising said branched chain saturated hydrocarbons, separating the alkylation products from the alkylating catalyst, fractionally distilling the said alkylation products into a synthetic gasoline fraction and a fraction containing hydrocarbons boiling above the gasoline boiling range and employing said fraction containing hydrocarbons boiling above the gasoline boiling range as said hydrocarbon liquid absorbing medium.

4. In a process for the production of branched chain hydrocarbons wherein olefins and isoparaffins are caused to react in the presence of a sulphuric acid catalyst, the steps of continuously recycling a mixture of isoparaffins, products of reaction and the acid in a closed system, continuously contacting gaseous olefins with a liquid absorbing medium, continuously introducing into said system gaseous olefins dissolved in said liquid absorbing medium and isoparaffins to be reacted, continuously withdrawing from said system a portion of the hydrocarbon-acid mixture, continuously settling said withdrawn mixture thereby obtaining a hydrocarbon phase containing the products of alkylation reaction and an acid phase, separating said phases, returning the acid phase into the closed reaction system for the alkylation of fresh quantities of isoparaffins and olefins introduced therein and employing a portion of the products of alkylation as said liquid absorbing medium.

5. A continuous process for the alkylation of isoparaffinic hydrocarbons having less than seven carbon atoms per molecule with normally gaseous olefins to produce branched chain saturated hydrocarbons boiling within the gasoline range, having high anti-detonating characteristics and substantially free from products of polymerization, which comprises continuously contacting the normally gaseous olefins with a liquid hydrocarbon absorbing medium to produce a liquid mixture containing the absorbed olefins, continuously introducing said liquid mixture and a substantially pure isoparaffinic hydrocarbon fraction boiling within a relatively narrow boiling range and maintained in a liquid state into a reaction zone, continuously introducing strong sulphuric acid into said zone to cause the interaction between the isoparaffins and the olefins to form products of alkylation, continuously recycling said hydrocarbon-acid mixture through said reaction zone, continuously withdrawing a portion of said mixture from the reaction zone, continuously separating said withdrawn mixture into an acid phase and a hydrocarbon phase containing the products of reaction and the unreacted isoparaffins, separately withdrawing said phases, commingling the hydrocarbon phase with an isoparaffin-containing hydrocarbon fraction, continuously conveying said mixture through a fractionating zone to recover therefrom the desired branched chain hydrocarbon fraction and a liquefied, substantially pure isoparaffinic hydrocarbon fraction having a relatively narrow boiling range, returning said last mentioned hydrocar-

bon fraction as the feed stock for the production of new quantities of branched chain hydrocarbons, wherein a fraction of the products of reaction comprises the absorbing medium for the gaseous olefins.

6. A continuous process for the alkylation of isoparaffinic hydrocarbons having less than seven carbon atoms per molecule with normally gaseous olefins to produce branched chain saturated hydrocarbons boiling within the gasoline range, having high anti-detonating characteristics and substantially free from products of polymerization, which comprises continuously contacting the normally gaseous olefins with a liquid hydrocarbon absorbing medium to produce a liquid mixture containing the absorbed olefins, continuously introducing said liquid mixture and a substantially pure isoparaffinic hydrocarbon fraction boiling within a relatively narrow boiling range and maintained in a liquid state into a reaction zone, continuously introducing strong sulphuric acid into said zone to cause the interaction between the isoparaffins and the olefins to form products of alkylation, continuously re-

5 cycling said hydrocarbon-acid mixture through said reaction zone, continuously withdrawing a portion of said mixture from the reaction zone, continuously separating said withdrawn mixture into an acid phase and a hydrocarbon phase containing the products of reaction and the unreacted isoparaffins, separately withdrawing said phases, commingling the hydrocarbon phase with an isoparaffin-containing hydrocarbon fraction, 10 continuously conveying said mixture through a fractionating zone to recover therefrom alkylated hydrocarbons boiling within the gasoline boiling point range, a heavy alkylated hydrocarbon fraction boiling above the gasoline boiling point range and a substantially pure isoparaffinic hydrocarbon fraction having a relatively narrow boiling range, returning the said isoparaffinic fraction having the relatively narrow boiling point range as the feed stock for the production of new 15 quantities of branched chain hydrocarbons and employing said heavy alkylated hydrocarbon fraction as the said liquid absorbing medium.
